METHOD AND MEANS FOR ELIMINATING FADING

Application filed May 2, 1928. Serial No. 274,274.

This invention relates to the elimination of what has come to be known in radio signalling and speed transmission systems as "fading". The invention as herein disclosed, 5 is particularly adapted for use in the reception of short wave radio signals and for use in locations where the effect of fading of signals is particularly troublesome, although it is to be understood that the system is likewise capable of efficient use for all types of 10 radio receiving systems, and is useful for long waves as well as short waves.

Considerable study in the art of short wave radio transmission and reception discloses 15 the fact that different locations have different fading characteristics and it is, therefore, conceivable that signals received upon geographically separated antennæ might be of a maximum intensity at any instant at one 20 point and a minimum intensity at the same instant at the other point and at a later instant the conditions might be exactly the reverse. This same condition and state of affairs has been found to hold true with a plurality of antennæ of different directive characteristics located at the same point and, while we will refer in this specification and 25 claims to the use of geographically separated antennæ for the purpose of describing and claiming our invention, it is to be particularly understood that the invention relates also broadly to antennæ of different directive characteristics located at the same point, 30 wherein a horizontal doublet might correspond to one antennæ and a vertical doublet might correspond to a geographically spaced second antennæ member, and in this last named arrangement both the horizontal and the vertical doublet would have different 35 directive characteristics.

An ideal condition for combining signals from various geographically spaced antenna systems would be to direct their separate energy to a common receiver and make a single 45 adjustment for phase displacement of the various antenna systems relative to each other, but experimentation has proved that this system will hold great limitations inasmuch as it has been found that the phase relationship between the signal voltage received at

one antenna and that received at another antenna having different directive properties or geographically spaced from the first antennæ changes from instant to instant.

It is, therefore, an object of our invention 50 to provide a method and means for combining signals from various geographically separated antenna systems or from antenna systems having different directive properties located at the same point, so that the signals 55 from the various antenna systems may be combined independently of the phase relationship of the signals received on any separate antenna system. The broad idea of this scheme of combining signals has been disclosed in our copending application, Serial 60 No. 78,708, filed January 2nd, 1926, as well as application Serial No. 261,737, filed March 15th, 1928, of which this application represents a modification and further development 65 of the broad idea set forth.

We have illustrated diagrammatic embodiments which our invention may assume by the accompanying drawing, wherein:

Fig. 1 illustrates the method of combining signals by the use of an artificial line in connection with a plurality of receiving antennæ; and,

Fig. 2 illustrates a modification of Fig. 1 showing the use of a three phase oscillator 80 for controlling the combination of signals from a plurality of receiving antenna systems.

It is to be distinctly understood that we are entitled to various modifications such as fall fairly within the spirit and scope of this invention, and we have resorted to the showing of the specific embodiments as illustrated by Figs. 1 and 2 of the drawing merely for the purpose of making a concrete illustration, but consider our invention as broad enough to all forms such as fall fairly within its scope as defined by the claims following the end of this specification.

To now make reference to Fig. 1 of the 95 drawing, we have shown a receiving system in which, for convenience of illustration, three antennæ systems designated 1, 2 and 3 have been indicated. The energy picked up on each of the antennæ systems 1, 2 and 3, which, as 100

above stated, may be geographically separate antennæ or antennæ located at a single point but having different directive characteristics, is carried through tuned circuits of any desired character such as 4, 5 and 6 which are all tuned to the same signal frequencies.

The energy as selected by the tuned circuits 4, 5 and 6 is then directed to the input electrode 7, 8 and 9 of the vacuum tubes, 10, 11 and 12 respectively. The output circuit of each of the vacuum tubes 10, 11 and 12 includes a source of plate potential which is connected to the terminal in each plate circuit designated as +B and this output circuit of the several vacuum tubes may be, if desired, coupled through couplings of either the electromagnetic or the electrostatic type which are designated as 13, 14 and 15 to direct energy from the several vacuum tubes to a common receiving circuit, generally designated 16, which is connected with a common receiver (not shown).

The grid returns from the several vacuum tubes, 10, 11 and 12 are then carried to several points 17, 18 and 19 on an artificial line, generally designated 20. The artificial line 20 preferably consists of series inductance 21 and shunt capacity 22. The capacity elements 22 are associated with a common side 30 of the artificial line which is grounded at 23 and with the inductance element 21. The artificial line is substantially a wave length long electrically for a particular oscillator frequency to be hereinafter described, although it is to be understood that this limitation is unnecessary. The capacity elements 22 constitute the capacity elements of this artificial line. Connected across the end of the artificial line 20 is a damping resistance 40 24 for the purpose of damping reflections which might be possible upon the line.

Coupled to the artificial line 20 through any desired form of coupling connection, as by the transformer 25, is an oscillator 26 which is preferably of the low frequency type, and may be either an audible frequency or a superaudible frequency.

As has been above stated, the grid returns of the vacuum tubes 10, 11 and 12 are connected to the artificial line at 17, 18 and 19. These different points of connection to the artificial lines may or may not be nodal points on the artificial lines, but preferably may be chosen as any point desired, of course, assuming that the artificial line is 360 electrical degrees long for the particular frequency of the oscillator 26. Where the line 20 is 360 degrees long the points of connection of the grid return leads preferably will be spaced substantially 120 electrical degrees apart, but here again this spacing of points is not essential to the operation of the invention, and the spacing may be of any desired 60 separation along the artificial line regardless

of how close or remote from a succeeding point.

The oscillator 26 which is coupled to the artificial line produces travelling waves down the artificial line toward the direction of the damping resistance 24, and it is readily seen that these traveling waves might at one instant give a maximum positive voltage at the grid return connection point 17 for the grid 7 of the tube 10, and at the same instant would be almost minimum or negative voltage at the grid return connections 18 and 19 of the tubes 11 and 12. This would mean at this particular instant a considerable amount of energy would be transferred to the output circuit of the tube 10 and very little energy would be found in the output circuit of the tubes 11 and 12, since under normal conditions the biasing batteries 27, 28 and 29 associated with the tubes 10, 11 and 12 respectively bias the grid elements 7, 8 and 9 to cut-off, but with the point 17 as grid connection of the tube 10 to the artificial line 20, becoming strongly positive, the tube 10 will no longer be biased to cut-off and with said positive bias on the grid 7 the tube will continue to pass plate current until the maximum positive voltage of the oscillator is removed from point 17 and the cut-off potential again applied to the grid from the "C" battery. However, at the next instant after the point 17 connection of the grid return from tube 10 has been subjected to the maximum positive voltage on the artificial line a maximum positive voltage might be found at point 18 of 100 connection of the grid return tube 11 to the artificial line, under which condition the bias battery 28 upon the grid 8 of the tubes 11 will be overcome and the tube 11 will commence to pass plate current and the signal 105 received upon the antenna tube and selected through the tuning means generally designated 16 will be transferred through the tube 11 and the coupling or transformer 14 through the circuit 16 which connects with the receiving system in a manner similar to that above set forth in regard to tube 10 and its associated antenna system 1. At this same period of time the points 17 and 19 for connecting the tubes 10 and 12 to the artificial line will

not be at a positive value but will be approaching a minimum value and the bias batteries 27 and 29 of the tubes 10 and 12 will control the grid potentials so that the tubes will be biased to cut-off. Under conditions when a maximum positive voltage attains at point 18 the tube 11 will be the only tube to transfer energy to the receiving system.

Under similar conditions at a later instant the point 19 will be at a maximum positive voltage and the points 17 and 18 will be at less positive voltages, so that in a manner similar to that described in connection with tubes 10 and 11 the tube 12 will transfer energy from the antenna system 3 through the 139

coupling transformer 15 to the circuit 16 of the receiving system, and at the same time the tubes 10 and 11 will be biased to cut-off.

It is thus seen that the outputs of the tubes 10, 11 and 12 are all coupled inductively with the input circuit 16 of a common receiving system, so that maximum energy from tube 10 will be transferred to the common receiving system at one instant, then at a later instant maximum energy from tube 11 and at a still later instant maximum energy from tube 12, and following with tube 10 in the manner described. These maximums periodically change so that irrespective of the phase relationship of the radio frequency energy picked up on the separate antenna systems 1, 2 and 3 the energy is directed to the common receiving means and the effects of fading and phase relationship are no longer detrimental and the energy can be combined absolutely and totally independent of any phase relationship of the signals at the various antennæ.

By Fig. 2 of the accompanying drawing we have shown a system which is a modified form of that shown by Fig. 1. By Fig. 2, in a similar manner to that shown by Fig. 1, signal energy is received and the geographically spaced antennæ systems or upon antenna systems of different directive characteristics located at a common point, which have been designated 101, 102 and 103 respectively. The energy received upon the antenna systems 101, 102, 103 is directed through any preferred or desirable form of tuned circuit 104, 105, 106 to the input electrode 107, 108, 109 of the vacuum tubes 110, 111 and 112 which each direct their output energy to a common receiving circuit 113 which is connected with a single receiving means (not shown). The output circuit of the tubes 110, 111, 112 embodies the primary winding of the coupling transformers, 114, 115 and 116 which are each associated with any desired form of plate supply energy indicated as +B. Each of the vacuum tubes 110, 111 and 112 has a bias battery designated 117, 118 and 119 respectively connected in the grid return lead.

In a manner similar to that above described in connection with the artificial line, the batteries 117, 118 and 119 in the grid return circuit of the tubes 110, 111 and 112 normally bias the grid member of these tubes down to cut-off so that, under normal conditions, no signals are transferred from the antenna systems 101, 102, 103 to the combining circuit 113 leading to the receiving apparatus for all of the antenna systems.

In contrast to the artificial line system and its associated modulator shown by Fig. 1 for controlling the various tubes associated with the receiver and adapted to transfer radio frequency energy to the common combining circuit, by Fig. 2 we have shown connections at 120, 121 and 122 for connecting

the terminals or leads connecting the terminals of a three phase oscillator of any desired character, and connected from the terminals 120, 121 and 122 in the form of a delta shaped net work. The windings 123, 124 and 125 form the primary winding of the transformers 126, 127 and 128 respectively. The secondary windings 129, 130 and 131 of the transformers 126, 127 and 128, respectively, are connected and form a part of the grid return circuit of the tubes 110, 111 and 112, respectively. It is thus clearly seen that one phase of the three phase oscillator is associated with the tube 110, another phase with the tube 111 and the third phase with the tube 112.

When voltage is induced in the grid circuit of the tube 110 through the secondary 129 of the transformer 126 due to the fact that phase number one of the three phase oscillator is at a maximum positive point in its value, the tube 110 will function normally and the bias 117 which normally prevents plate current flow is overcome so that the grid member 107 is no longer biased to cut-off and the tube functions normally and amplifies the radio frequency energy input from the antenna system 101 and passes this energy on through the common receiver by means of the output transformer 114 which has its secondary winding, as above described, associated with the common combining circuit 113 for all of the various tubes in the system and forming a secondary winding in series with the secondary winding of the output transformer associated with the vacuum tubes 111 and 112. At the instant when the voltage induced in the secondary 129 of the transformer 126 reaches a maximum value, the voltage induced in the secondary windings 130 and 131 of the transformers 127 and 128 so as to influence the grid members 108 and 109 of the tubes 111 and 112 will approach a minimum value due to the local three phase oscillator, because of the fact that in the three phase system of supply, the voltage vectors are 120 electrical degrees apart. In this case, therefore, there is maximum radio frequency energy being passed through the tube 110 and very little energy or none at all being passed through the tubes 111 and 112 due to the fact that the voltage induced in the secondaries 130 and 131, above named, being of a minimum value and the bias in batteries 118 and 119 being sufficient to bias the tubes to cut-off.

In a manner similar to that described in connection with tube 110, at some time after the voltage induced in the grid circuit of tube 110 reaches a maximum value the voltage on the grid 108 of the tube 110 will be of a maximum value and tube 111 will then pass maximum energy to the common combining circuit 113 and the tubes 110 and 112 will pass minimum energy or none at all.

because of the bias applied, in a similar manner to that above described, because of the fact that the voltage induced in the grid circuit of the separate tubes are still 120 electrical degrees apart. Similarly, at a later instant the tube 112 will pass maximum energy to the combining circuit and the tubes 110 and 111 will pass minimum energy, after which the tube 112 passes energy to the combining circuit the tube 110 will then be free to pass its maximum energy and the circle of operation will be continued.

When the voltage induced in the grid circuit 107 of the tube 110 due to the local three phase oscillator reaches its maximum negative value, it will aid the "C" battery 117 in biasing the tube 110 to cut-off so that no radio frequency energy will pass through the tube 110 and its associated output transformer 114 so as to direct itself to the common combining circuit 113. In a similar manner when the voltage from the three phase oscillator reaches a maximum negative value in the coils 124 and 125 the grids of the tubes 111 and 112 will be similarly biased to cut-off, since this maximum negative voltage will aid the "C" batteries 118 and 119 respectively and their radio frequency output will be furnished from the tubes 111 and 112 in a similar manner to that described in connection with tube 110.

It is, therefore, readily apparent that in the case last described of the three phase oscillator that the grids of the tubes may be periodically biased so that the three input tubes 110, 111 and 112 will be biased to cut-off and at first, one tube will pass maximum energy, then the next one will pass maximum energy, and lastly the third tube will pass maximum energy through to the common receiving system, and the input signal phase will be entirely dissociated. It is readily seen, therefore, that this system will function in a similar manner to that described in connection with the artificial line of Fig. 1. In this case also, it is immaterial what the phase relationship of the radio frequency signal energy upon the antenna 101, 102 and 103 may be, since the signals can, as has been above described, be combined absolutely independent of the phase relationship.

While we have described the system of Fig. 1 and the system of Fig. 2 as applicable to three geographically spaced antennae spaced at the same point, but having different directive characteristics it will be apparent that the system may be used for two antenna systems or more than three antenna systems by appropriate correction of the number of phases for the oscillator of Fig. 2, or appropriate positioning of the contact point for the grid return circuits of Fig. 1 to the artificial line 20 and, therefore, the system is one which readily lends itself to

any number of antenna systems as may be chosen and be desirable.

It, therefore, can be understood that our invention is not restricted to the concrete examples which may be assumed from the drawing; and is not limited and should be understood in its broadest terms, and it should be apparent that it is through schemes for eliminating the detrimental effects of fading that commercial operation of communication on short wave length is made possible, therefore, we wish our invention to be limited only in so far as it is necessary to limit the same from the scope of the following claims:

Having now described our invention, what we claim and desire to secure by Letters Patent is:

1. The method of avoiding the effects of fading on radio signals which includes, receiving the same signals at a plurality of points and producing therefrom a plurality of signal effects, directing the said signal effects to a common receiving system for all of said receiving points, and continuously cyclically and consecutively associating each of said receiving points with said common receiving system.

2. Apparatus for avoiding the effects of fading on radio signals which includes, a plurality of antennae for receiving the same signal, each of said antennae having different instantaneous response characteristics to the same signal effects, a common receiving point, means for directing the energy from said receiving point to said common receiving point, and means for continuously cyclically and successively associating one of said points with said common receiving point.

3. The method of overcoming fading effects when receiving radio signals with receiving antennae of different instantaneous response characteristics and a radio frequency combining circuit which comprises, receiving the same signal bearing waves upon each of said antenna systems to produce a plurality of radio frequency signaling effects, continuously and successively associating each of said antenna systems with said radio frequency combining circuits, deriving signals in said combining circuit from said different antenna systems at successive and predetermined periods from each of said antenna systems, combining said derived signals and obtaining the transmitted signals from the combined signals.

4. The method of avoiding the effects of fading of radio signals which includes, receiving the same signal at a plurality of receiving points each exhibiting different instantaneous response characteristics to the same signal, producing from said received signals a plurality of signal effects, introducing to each of said produced signal effects the effects of a low frequency, and alternatively and successively associating each of said re-

- ceiving points with a common receiving system, and interrupting the association of each of said separated receiving points with said receiving system at said low frequency rate.
5. The method of avoiding the effects of fading on radio signals which includes, receiving the same signal at a plurality of points of different instantaneous response characteristics and producing therefrom a plurality of signal effects, associating each of said plurality of points with a common receiving system for all of said reception points, biasing each of said receiving points normally to cut-off, removing said cut-off bias from said points successively and continuously at a low frequency rate, and receiving the effect from the signal as received at said plurality of points interruptedly and successively in said common receiving system.
10. 6. The method of avoiding the effect of fading on radio signals which includes, receiving the same signal at a plurality of points of different instantaneous response characteristics and producing therefrom a plurality of signal effects, associating each of said plurality of points with a common receiving system for all of said receiving points, normally biasing each of said receiving points to cut-off, removing said cut-off bias from said point successively and continuously at an audible rate, and receiving the effect of the signal as received at said plurality of points interruptedly and successively in said common receiving system.
15. 7. A system for the elimination of fading on short wave lengths which includes, a plurality of receiving means of different instantaneous response characteristics, a receiving circuit associated with each of said receiving systems and adapted to combine the energy from all of said systems, means for biasing each of said receiving systems normally to cut-off, and means for alternatively and successively removing the bias from said receiving systems and associating in succession said receiving means with said receiving circuit.
20. 8. A system for the elimination of fading which includes, a plurality of receiving antennæ each having different instantaneous response characteristics to the same signal effect, a vacuum tube amplifier for transferring the effect received upon each of said antenna systems, a common receiving circuit for all of said antenna systems, said receiving circuit being associated with the output of all of said vacuum tube amplifiers, means for normally biasing each of said amplifiers to cut-off, and means for successively and continuously removing the bias from one of said amplifiers, whereby said amplifier passes received signal energy to said combining circuit and the remainder of said amplifiers are blocked with respect to the received signal energy and at each instant only one of
- said amplifiers is associated with said receiving circuit.
9. A system for the elimination of fading which includes, a plurality of receiving antennæ each having different instantaneous response characteristic to the same signal effect, a vacuum tube amplifier for transferring the signal effects received upon each of said antenna systems, a common receiving circuit for receiving the signals from all of said antenna systems, a coupling means for associating said receiving circuit with the output of all of said vacuum tube amplifiers, means for normally biasing each of said amplifiers to a cut-off potential, and means for successively and continually removing the said cut-off bias from one of said amplifiers at a low frequency rate, whereby said amplifier passes received signal energy to said common receiving circuit and the remainder of said amplifiers are blocked with respect to the received signal energy and at each instant only one of said amplifiers is associated with said receiving system.
25. 10. A system for eliminating the effects of fading of signals in radio signalling apparatus which includes, a plurality of receiving antenna systems each having different instantaneous response characteristic to the same signal, a single receiving circuit for all of said antenna systems, a vacuum tube relay system for coupling each of said antenna systems with said single receiving system, means for normally maintaining a cut-off bias potential upon each of said vacuum tube relays, means for cyclically removing said cut-off bias potential from said relays and simultaneously associating each of said antenna systems and associated relays and its associated relay with said receiving circuit.
30. 11. A system for the elimination of fading of signals in radio signalling apparatus which includes, a plurality of receiving antenna systems each having different instantaneous response characteristic to the same signal, a vacuum tube relay system associated with each of said antenna systems, a single combining circuit for all of said antenna systems inductively associated with the output of each of said vacuum tubes, means for biasing the input electrode of each of said vacuum tubes to a predetermined cut-off potential, an artificial line, a connection between the grid electrode of each of said vacuum tubes and a point on said artificial line, a low frequency oscillator inductively coupled with said artificial line for producing wave trains propagating the length of said artificial line and means provided by said oscillator for successively and continuously applying a positive potential bias to the grids of said tubes for overcoming the cut-off bias and successively and con-

- tinuously associating each of said vacuum tubes with said common receiving system, whereby the effects of fading are substantially reduced in said receiving system.
5. 12. A system for the elimination of fading of signals in radio receiving apparatus which includes a plurality of receiving antennæ of different instantaneous response characteristics, an amplifier associated with each of said antenna systems, a common receiving circuit for receiving the signal effects from all of said antenna systems, means for coupling each of said amplifiers with said common receiving circuit, means for normally maintaining a 10 cut-off potential upon each of said amplifiers, whereby signal energy reaching each of said amplifiers is blocked from said common receiving circuit, an oscillator and means for associating each of said amplifiers with said oscillator whereby the cut-off bias potential is cyclically and successively removed from each of said amplifiers and the said amplifiers successively pass signal energy into said common receiving circuit and the signals received upon said plurality of antennæ are combined in said receiving circuit independent of the phase relationship at the antenna and the effects of fading are substantially eliminated.
15. 13. The method of overcoming fading effects during signalling which includes collecting in characteristically different fashions signal bearing transmitted energy at a plurality of separated points, and continuously and in predetermined sequence translating the energy collected at each point in order to obtain the transmitted signal.
20. 14. The method of overcoming fading effects during signalling which includes collecting signal bearing energy at a plurality of separated points, producing potential waves, utilizing the waves produced to control the successive translation of the energy collected at each of the points, and combining the translated energy to obtain the transmitted signals.
25. 15. The method of reducing fading during radio signalling which includes collecting electromagnetic energy of like frequency at a plurality of points and translating successively and in predetermined order the energy collected at each point.
30. 16. The method of reducing fading during radio signalling which includes collecting electromagnetic energy of like frequency at a plurality of separated points, and translating successively and continuously in predetermined order the energy collected at each point automatically.
35. 17. The method of reducing fading during radio signalling which includes collecting electromagnetic energy of like frequency at a plurality of separated points and translating successively at a supersonic frequency the energy collected at each point.
40. 18. Radio signalling apparatus for overcoming fading of signal bearing radio waves comprising means for collecting electromagnetic energy of like frequency at a plurality of points, means for successively and in predetermined order translating the energy collected at each point, and means for deriving transmitted signals from the translated energy.
45. 19. Radio signalling apparatus for overcoming fading of signal bearing radio waves comprising means for collecting electromagnetic energy of like frequency at a plurality of separated points, means for automatically and successively and continuously in predetermined order translating the energy collected at each point, and means for deriving transmitted signals from the translated energy.
50. 20. Radio signalling apparatus comprising means for collecting electromagnetic energy of like frequency at a plurality of separated points and means for translating successively at a supersonic frequency the energy collected at each point.
